Primary Examiner — Cathron C Brooks*Assistant Examiner* — Ian F Whitmore(74) *Attorney, Agent, or Firm* — Pearne & Gordon LLP(57) **CLAIM**

The ornamental design for a display screen with graphical user interface, as shown and described.

DESCRIPTION

FIG. 1 is a front view of a first embodiment of a display screen with graphical user interface showing our new design;

FIG. 2 is a front view thereof, with the area that is shown enlarged in FIG. 3 demarcated by dot-dash line;

FIG. 3 is an enlarged view of area 3 as indicated by the dot-dash lines in FIG. 2;

FIG. 4 is a front view of a second embodiment of a display screen with graphical user interface showing our new design;

FIG. 5 is a front view thereof, with the area that is shown enlarged in FIG. 6 demarcated by dot-dash line; and, FIG. 6 is an enlarged view of area 6 as indicated by the dot-dash lines in FIG. 5.

The outermost dashed broken-line rectangle illustrates the perimeter of a display screen. The remaining dashed broken lines illustrate portions of the graphical user interface. The dot-dash broken lines in FIGS. 2 and 5 indicate a portion of the display screen that is shown enlarged and isolated in FIGS. 3 and 6, respectively.

The dot-dash broken lines in FIGS. 3 and 6 illustrate the perimeter of the corresponding display screen portion. The broken lines form no part of the claimed design.
